TELEPHONE SYSTEM.

APPLICATION FILED FEB. 2, 1903. RENEWED MAY 17, 1905.

UNITED STATES PATENT OFFICE.

FRANK B. COOK AND JAMES G. NOLEN, OF CHICAGO, ILLINOIS; SAID NOLEN
ASSIGNOR TO SAID COOK.

TELEPHONE SYSTEM.

No. 856,570.

Specification of Letters Patent.

Patented June 11, 1907.

Application filed February 2, 1903. Renewed May 17, 1905. Serial No. 260,857.

To all whom it may concern:

Be it known that we, FRANK B. COOK and JAMES G. NOLEN, citizens of the United States of America, and residents of Chicago, Cook county, Illinois, have invented a certain new and useful Improvement in Telephone Systems, of which the following is a specification.

Our invention relates to telephone systems in general.

Prior to our invention, it has been the practice to equip telephone systems with either annunciators or relays and lamps for enabling the subscribers to signal the operator. If annunciators are employed, the signaling current sent over the line by the act of the subscriber in calling up central serves to energize the electro-magnet of the annunciator and thereby cause the drop or shutter of the annunciator to fall, and thus, give a signal. In a similar manner, a call sent in by a subscriber will energize the electro-magnet of a relay, causing it to attract its armature and thereby close the local circuit of a signal lamp. In either case, however, it is obvious that the magnetism of an electro-magnet must be depended upon to effect the desired signal. Now electro-magnetic devices of this character—that is to say, annunciators, relays, and like devices—have given more or less trouble and are open to objections in various ways. For example, devices of this character are more or less expensive to manufacture and install, and are not always reliable in use. Relays are all provided with circuit-closing and opening contacts, and it often happens that these contacts become corroded or covered with dust, and thus fail to properly close the circuit when the relay is energized. Again, electro-magnetic devices of this character are all capable of offering more or less impedance or retardation to voice currents, and are also usually of such character as to present considerable resistance to battery current. These and other objections which are well known to those skilled in the art, have tended to render the use of annunciators, relays, and the like, more or less unsatisfactory.

The object of our invention, generally stated, is, therefore, the provision of a telephone system involving suitable calling and supervisory signals, such, for example, as electric lamps, but involving neither annunciators, relays, nor like electro-magnetic switches.

A special object is the provision of a form of automatic switch which will offer no impedance or retardation to voice currents, and which will not offer an undesirable amount of resistance to battery current.

Another object is to provide a form of automatic switch which can be cheaply manufactured and easily installed.

A further object is to provide a switching device of this character which will be absolutely dust proof.

It is also an object to provide certain details and features in a switch of this particular character tending to increase its general efficiency and serviceability.

Other objects and advantages will, however, hereinafter more fully appear.

Broadly considered, our invention contemplates a telephone exchange system without annunciators, relays, or electro-magnetic switches of any kind whatever.

More specifically, our invention contemplates a telephone system equipped with electro-thermal switches for operating the signals. As each switch involves merely a heat-concentrating member and an expansible medium, together with one or more contacts, it follows that a switch of this character would offer no impedance or retardation to voice currents, and that its resistance to battery current will not in any way be objectionable. Furthermore, as the heat-concentrating member and the expansible medium, and also the circuit-closing contacts may be sealed in a glass tube or bulb, it also follows that a switch of this nature is absolutely dust-proof and air tight. Again, the construction is so simple that a switch of this character can be manufactured at a cost far below that of the ordinary annunciator or relay.

In the accompanying drawings,—Figure 1 is a diagram illustrating a telephone system embodying the principles of our invention: Fig. 2 is an enlarged sectional view of one of the electro-thermal switches employed in the circuit arrangement shown in Fig. 1: Fig. 3 illustrates a modified arrangement in which the heating coils or heat-concentrating members of the electro-thermal switch are located directly in the talking circuit.

As thus illustrated, the general construc-

tion and circuit arrangement of the system can be of any suitable, known, or approved character. For example, the subscriber's apparatus at station A can be suitably connected with the switchboard apparatus B at the central station. In the same manner, the subscriber's telephone apparatus at substation C can also be suitably connected with the switchboard apparatus at the central station. This switchboard apparatus may comprise the usual spring-jacks b, b' , which are connected with the line leading to the substation A, and also the similar spring-jacks b^2, b^3 , which are connected with the line leading to substation C. The switchboard apparatus may also comprise the usual cord circuit consisting of the answering-plug b^4 and the calling-plug b^5 , the two plugs being connected by a plurality of cord strands. A calling or line-lamp signal b^6 of the usual character can be associated with the answering-jack of the line leading to the substation A, while a similar lamp signal b^7 can be associated with the answering-jack allotted to the line of substation C. The supervisory lamps b^8 and b^9 , which are connected in the third strand of the cord-circuit, can be of the usual form or character. With the circuit arrangement shown, a single electro-thermal switch D is associated with the line allotted to substation A, while a similar electro-thermal switch E is associated with the line leading to substation C. The relative arrangement of the different instruments involved in the system, and also the construction of the different circuits, will, however, be more fully understood by considering the various operations and circuit connections which take place in connecting up one subscriber with another.

In Fig. 1, the subscriber at substation A is supposed to have just lifted his receiver a from the hook-switch a' , thereby closing the line circuit from the said switch through the contact-point 1, and the primary 2 of the induction coil, through the transmitter 3 and the conductor 4, through the main line conductor 5, through the conductor 6 on the switchboard at the central station, through the coil or heat-concentrating member 7 of the electro-thermal switch D, through the conductors 8 and 9, through the impedance coil 10 and the conductor 11 to the negative pole of the centralized battery or source of current 12, through the latter and its positive pole to the conductor 13, through the latter and impedance coil 14, thence through the other coil or heat-concentrating member 15 of said electro-thermal switch, through the other limb or conductor 16 of the line leading to the substation A, thence to said hook-switch. The line circuit thus closed causes the current flowing through the coils or heat-concentrating members 7 and 15 to generate

portion of the leg d of the electro-thermal switch, thereby causing the spirits or other conductive medium d' to be partially displaced into the other leg d^2 . This displacement of the conductive medium in the electro-thermal switch operates to close a local circuit from the battery 12, through the conductor 13 and the resistance 17, through the contact-point 18, and the said conductive medium d' , through the other contact-point 19 and the conductor 20, thence through the line lamp b^6 , through the conductors 21 and 9, and thence through the impedance coil 10 and the conductor 11 to the other pole of said battery. The resistance of the coil 17 is such that the closing of this local circuit permits only just enough current to flow through such circuit to light the said lamp. The operator, observing this signal, then inserts the answering plug of the cord-circuit in the answering jack allotted to the line of substation A, and then communicates with the calling subscriber in the usual manner, so as to receive the order for connection. When the answering plug is inserted in the jack allotted to the line of substation A, the connection thus established serves to place the supervisory lamp b^8 in parallel with the line lamp b^6 , thus shunting the latter out. For, as explained, the resistance of the coil 17 is such that only sufficient current to light the line lamp can pass. Thus, in answering the call, the operator automatically extinguishes or restores the line lamp signal.

Upon receiving the order for connection, the operator then inserts the calling plug in one of the multiple jacks allotted to the line of substation C, and then proceeds to call up the subscriber at this station in the well known manner. The act of inserting the calling plug in the multiple jack connected with the line leading to substation C completes a local circuit through the other supervisory lamp b^9 in the following manner: Current from the positive pole of the battery 12 flows through conductors 22 and 23, through the resistance coils 24 and 25 in parallel, through the conductive medium e of the electro-thermal switch E, through the conductor 26 and the testing ring 27 of the jack, through the sleeve 28 of the plug, thence through the said lamp b^7 , through the conductors 29 and 30, and thence to the negative pole of the battery. The resistance of the coil 24 is, like the coil 17, of a character to permit only sufficient current to pass to light the line lamp signal, and is of sufficiently high resistance to prevent the passage of sufficient current to light two lamps in parallel. But inasmuch as the shifting conductive medium e in the electro-thermal switch E is in its normal position when the operator plugs in for the purpose of calling the subscriber at substation C, it follows that a shunt consisting of the coil 25 and the

said conductive medium is at such time closed around the resistance coil 24, thereby lowering the resistance of the supervisory lamp sufficiently to permit the latter to glow. 5 This lamp thus caused to display a signal, continues to glow until the subscriber at substation C takes down his receiver, and thus closes the line circuit. When the subscriber at substation C removes his receiver *c*, therefore, by allowing the hook-switch *c'* to rise, a line signal is immediately completed from said hook-switch through contact-point 31, and the primary 32 of the induction coil, through the transmitter 33, thence through the limb 10 or line conductor 34 to the central station, through the coil or heat-concentrating member *e'* of the electro-thermal switch *E*, through the conductor 35 and the impedance coil 36, through the conductor 37 to the negative pole of the battery 12, through the latter to the conductor 22, thence through the impedance coil 38 and the conductor 39, through the other coil or heat-concentrating member *e²* of the said electro-thermal switch, 15 through the other limb or line conductor 40, and thence to said hook-switch, which completes the circuit. The current flowing through this circuit causes the coils *e'* and *e²* to generate sufficient heat to expand the gas 20 in the leg *e'* of the electro-thermal switch sufficiently to cause the shifting conductive medium *e* to become slightly displaced or shifted into the other leg *e²*. This, as in the previous case, connects two contacts in the 25 electro-thermal switch, and in this case the contacts 41 and 42, thereby closing the circuit from the said battery through the line lamp *e²*. But at the same time it will be seen that the conductive medium has shifted out of 30 contact with the other contact 43 of the electro-thermal switch, thereby opening the shunt extending around the resistance coil 24. Thus, although a local circuit has been completed through the line lamp *b²*, the latter 35 does not light up or glow, inasmuch as this lamp is still in parallel with the lamp *b¹*, and inasmuch as the resistance of the coil 24 will not permit the passage of sufficient current to light the two lamps in parallel. In this way, 40 the line lamp allotted to the called subscriber's line does not light up or glow when the said subscriber answers the call, but at the same time the automatic restoration or extinguishment of the supervisory lamp *b²* advises the operator that the subscriber has 45 answered the call. The two subscribers are now connected by a complete metallic talking circuit which, of course, includes the tip and ring contacts of the jacks and plugs, and 50 also the tip and ring strands 44 and 45 of the cord circuit. The talking circuit thus established is, it will be seen, preferably divided into two inductively connected halves or portions by the condensers 46 and 47, which are 55 interposed in the said tip and ring strands of 65 the cord-circuits.

Now when the subscribers have finished their conversation and when the receivers at the two substations have been returned to their normal positions on the hook-switches, 70 the line circuits through the coils or heat-concentrating members of the two electro-thermal switches are thereby opened and the shifting conductive medium of each electro-thermal switch is of course allowed to return 75 by gravity to its normal position. And at this juncture it is important to note that the battery current has continued to flow through the said coils or heat-concentrating members of the two electro-thermal switches 80 during the conversation between the two subscribers. In other words, closed battery circuits are maintained through the heat-concentrating members of the two electro-thermal switches as long as the subscribers' 85 receivers are off the hooks. But now, as stated, the return of these receivers to their respective hook-switches opens the line circuits, and permits the coils or heat-concentrating members in the electro-thermal 90 switches to cool off, and thereby allow the expansive medium in said switches to contract and cause the shifting conductive medium to assume its normal condition. This action, in each case, and as previously 95 explained, causes a shunt to be closed around each of the two resistance coils 17 and 24, thereby lowering the resistance of each supervisory lamp circuit sufficient to permit both lamps to glow. And, furthermore, the 100 return of the conductive medium to its normal condition in the two electro-thermal switches opens the circuit of each line lamp signal, thus opening the shunt or parallel connection extending around each supervisory 105 lamp. In other words, when the receiver at substation A is hung up, the conductive medium *d'* then returns to its normal position, and thereby establishes the normally closed shunt connection around the resistance coil 110 17, which shunt connection comprises the resistance coil 48 and the said conductive medium *d'*. The resistance of the coil 17 thus being materially shunted, sufficient current then flows through the local circuit including these two coils 17 and 48 to cause the lamp *b²* to glow. And in a similar manner, the hanging up of the receiver at substation C closes the shunt connection consisting of the coil 25 and the conductive medium *e*, 115 thereby so materially shunting the resistance of the coil 24 that sufficient current then flows through the local circuit to cause the lamp *b¹* to glow. Thus one electro-thermal switch is allotted to each line, and these electro-thermal switches not only control the line signals, but also control the supervisory 120 signals. That is to say, one electro-thermal 125

switch is allotted to each line, and each switch is under the control of the subscriber for the purpose of first causing the line signal to glow, and then, after the call has been answered and the plug inserted, for causing the supervisory lamp in the cord-circuit to glow for the purpose of giving the operator a signal for disconnection.

The construction of the electro-thermal switches can be varied considerably without departing from the spirit of our invention.

Fig. 2 illustrates the construction of the electro-thermal switch E, shown in Fig. 1. The conductive medium e can be of any suitable character, as, for example, it may consist of a sufficient quantity of spirits. Again, it may consist of mercury or mercury and spirits. It is preferable, however, to seal the said conductive medium and the coils or heat-concentrating members e' , e'' up in a vacuum, so as to prevent oxidation of any of the elements thus inclosed in the glass tube or bulb; and under such conditions the conductive medium e is preferably of a character to evaporate slightly and thereby provide a sufficient quantity of expansive gas to enable the heat generated by the coils or heat-concentrating members to effect the desired displacement of the conductive medium. With an automatic switch of this character, the coils or heat-concentrating members can, if desired, be placed in any of the circuits through which it is necessary for voice currents to travel, and under such conditions the coils or heat-concentrating members offer no impedance or retardation, such as is characteristic of a relay or annunciator. And, furthermore, a switching device of this character is peculiarly adapted to a circuit arrangement which necessitates a constant flow of battery current through the switch during the time the subscribers are talking, such, for example, as the circuit arrangement shown in Fig. 1. That is to say, in a circuit arrangement such as shown in Fig. 1, a flow of battery current is necessarily maintained through the automatic line switches during the conversation between the two subscribers, inasmuch as it is the restoration of these switches to their normal conditions which operates to cause a display of the supervisory signals. To thus maintain a flow of battery current through an ordinary line relay during a long conversation would result in an injurious and undesirable heating of the relay. But inasmuch as our improved line switch is dependent upon the generation of heat for its operation, and is thus inherently thermal in character, it follows that a constant flow of battery current can have no injurious effect, and that the subscribers can carry on their conversation for any length of time without in any way injuring the automatic line switches, which remain operated during such conversation. With the arrangement illustrated,

what little resistance the heat-concentrating members offer to the flow of battery current is equally balanced—one member being located in one side of the line circuit, and the other member being located in the other side of said circuit. Inclosed, as they are, within a hermetically sealed glass tube or bulb, the various contacts can never become oxidized, and consequently the closing of the circuit is always of a certain and positive character.

It will be readily understood that we do not limit ourselves to any particular form or construction of electro-thermal switch.

As far as the broader purposes of our invention is concerned, the test which the operator usually makes for the purpose of ascertaining whether a line is busy, before a connection is made with such line, can be made in the usual way by touching the tip of the calling plug to the test ring of the jack connected with the called subscriber's line. For example, as shown in Fig. 1, the test circuit, when the called subscriber's receiver is off the hook and when no plugs are in any of the jacks connected with his line, will extend from the negative pole of the battery and will include the line lamp, the contacts 42 and 41, the testing ring of the jack, the tip contact and tip strand of the cord-circuit, and one coil of the operator's head telephone X in the cord-circuit of the operator making the test and back to the other pole of the battery 12. Now, on the other hand, should it happen that the called subscriber's line is busy,—that is to say, that his receiver is off the hook and the plug of one of the cord-circuits is in a jack connected with his line, then, in such case, the test circuit completed by the act of another operator touching the tip of her calling plug to the jack connected with his line, will not only include the supervisory lamp, but also the line lamp, it being observed that the two are then connected in parallel. Thus in either case, the test circuit includes the line lamp, either alone or in parallel with the supervisory lamp, and in either case a local circuit is completed from one pole of the battery to the other which includes the operator's head telephone, and in either case, the constant flow of current through this closed local circuit will serve in the usual and well known manner to advise the operator that the line is already in use. It will be understood that the test circuit in either case, but particularly when a subscriber has simply taken down his receiver and has not received an answer from central, includes the liquid conductive medium of the electro-thermal switch. Suppose, however, that the called subscriber has already been called by another operator but has not yet responded. Now, in such case, the test circuit will obviously only include the supervisory lamp in the cord-circuit of the operator making the test. These test circuits

may, however, like the balance of the circuits be modified or changed to any extent without departing from the spirit of our invention, as far as the broader aspect of the invention is concerned. If the line is busy, in any of the three ways indicated, a click will be produced in the operator's head telephone, indicating that the line is either in use or being held for use. But if there are no plugs in any of the jacks, and if the subscriber's telephone is on the hook, then there will be no click in the operator's telephone. But this method of testing is well understood by those skilled in the art and need not be further described.

The fact that our improved electro-thermal switch or circuit-closing and breaking device is non-inductive in character is of great importance, especially in connection with circuits where it is found desirable to locate the coils or heat-concentrating members directly in the talking circuit. For example, in Fig. 3 the two coils of the electro-thermal switch constitute a part of the line connection between the jacks and the line conductors, and are consequently directly in the talking circuit. But even when thus arranged, these coils or heat-concentrating members can offer no retardation or impedance to voice currents, inasmuch as they are obviously non-inductive in character, and not capable of offering impedance or retardation to voice currents in the manner which is necessarily characteristic of a relay, annunciator, or other similar device involving a helix and soft iron core. Thus, as explained, our invention contemplates an automatic switch which is non-magnetic and non-inductive in character, and which may, therefore, be located in any of the conductors of a telephone system, regardless of whether or not these conductors are employed for talking purposes.

I claim as my invention:

1. In a telephone system, the combination of a subscriber's line, a line lamp signal, a centralized source of current connected with the line, a subscriber's hook-switch for opening and closing the line circuit, a normally open circuit including said lamp signal and source of current, and a non-inductive switch associated with the line at the central station and so connected with the line as to be controlled by said hook-switch, said local circuit also including the normally open contacts of said non-inductive switch.

2. In a telephone system, the combination of a subscriber's line circuit, means for supplying current to said circuit, a line lamp signal associated with the line at the central station, a normally open local circuit including said lamp and source of current, and a non-inductive circuit-closing device adapted to be operated by current flowing through said line

circuit and adapted for closing said local circuit. 65

3. In a telephone system, the combination of a subscriber's line circuit, a centralized battery for supplying current to said line circuit, means at the subscriber's station for opening and closing the line circuit, an electro-thermal switch associated with the line at the central station and adapted to be controlled by the subscriber, and a line signal connected and arranged to be controlled by 75 said switch.

4. In a telephone system, the combination of a subscriber's line circuit, means under the control of the subscriber for causing a flow of current in said line circuit, a visual signal associated with the line at the central station, and a thermal device for controlling the display of said signal, said device being in turn under the control of the subscriber. 80

5. In a telephone system, the combination of a subscriber's line circuit, means under the control of the subscriber for supplying current to said circuit, line and supervisory signals located at the central station, and a single non-inductive and non-magnetic electro-thermal circuit-closing device connected and arranged for controlling both of said signals, and adapted to be controlled by means located at the subscriber's station. 85

6. A telephone system comprising substations equipped with suitable substation apparatus, a central station equipped with suitable switchboard apparatus, suitable line connection between the switchboard apparatus and the substations, said switchboard apparatus including line and supervisory visual signals, and also including a plurality of electro-thermal switches, one for each line, adapted to be controlled by means located at the substations, and adapted in turn to control the display of said signals. 90

7. In a telephone system, and in combination with subscriber's telephones and operator's plugs and connecting cords and with a visual signal and a battery for operating the same at the central station, a circuit-closing device for said signal consisting of a hermetically sealed receptacle, and of a suitable heat concentrating member and expansive medium, together with suitable contacts and a conducting medium inclosed within said receptacle. 100

8. In a telephone system, and in combination with subscriber's telephone and operator's plugs and connecting cords and with a visual signal and a battery for operating the same at the central station, a circuit-closing device consisting of a hermetically sealed receptacle, and of a heat-coil and expansive medium, together with suitable contacts and a conducting medium, included within said receptacle. 110

9. In a telephone system, the combination of a subscriber's line circuit, a line lamp sig-

- nal, a centralized source of current supply, a circuit-closing device for controlling the display of said signal, said device being under the control of means located at the subscriber's station, and including normally open contacts, an expansible medium and means for expanding the same, and a shiftable quantity of conductive liquid for closing said contacts.
10. In a telephone system, the combination of a subscriber's line circuit, centralized means under the control of the subscriber for supplying current to the line circuit, a line lamp signal, and a non-inductive, non-magnetic circuit-closing device for controlling the display of said signal, said device including normally open contacts an expansible medium and means for expanding the same and a conductive liquid for closing said contacts.
15. In a telephone system, the combination of a subscriber's line circuit, centralized means under the control of the subscriber for supplying current to the line circuit, line and supervisory signals at the central station, and a non-inductive and non-magnetic electro-thermal circuit-closing device associated with the line at the central station, adapted for controlling the display of both the said signals, said device being arranged and connected to remain operated while the line circuit is closed.
20. In a telephone system, the combination of a subscriber's line circuit, a line lamp signal, a battery for supplying current for lighting said lamp, a circuit closing device for controlling the display of said signal also operated by current from said battery, said device including a shiftable quantity of conductive liquid, and a normally open local circuit including said lamp and battery, and also including said liquid.
25. In a telephone system, the combination of a subscriber's line circuit, centralized means under the control of the subscriber for supplying current to the line circuit, a line lamp signal, an electro-thermal switch under the control of the subscriber and adapted for controlling the display of said signal, said switch including a quantity of conductive liquid, an operator's cord-circuit having a receiver or head telephone connected with said means for supplying current, a jack connected with the subscriber's line provided with a test ring, and a normally open test circuit which includes said operator's head telephone, and which also includes said liquid.
30. In a telephone system, the combination of a plurality of subscribers' lines, means for supplying current, a line signal associated with each subscriber's line, electro-thermal switches for controlling the flow of current through said line signals, subscriber's manually operated switches for controlling the flow of current through said electro-thermal switches, and means for connecting the sub-

scriber's lines one with the other, said electro-thermal switches each comprising a suitable resistance for generating heat, a confined body of gas associated with said resistance, suitable switch contacts, and means actuated by the expansion of said gas for operating said contacts.

15. In a telephone system, the combination of a plurality of subscribers' lines, means for connecting said lines one with the other, suitable circuit connections and means for supplying current, signaling devices for the said lines, and a self-restoring electro-thermally operated switch associated with each of said lines for operating the said signaling devices.

16. In a telephone system, the combination of a telephone line extending from a subscriber's station to a connection terminal at a central station, an electro-thermal switch and a source of electricity in circuit with a portion of the said line, a signaling device associated with the line and arranged to be operated by the said switch, a suitable connecting circuit for the line, and means for rendering the said signaling device inert while connection is made with the line.

17. In a telephone system, the combination of a telephone line extending from a substation to connection terminals at a central station, an electro-thermal switch and a source of electricity in a branch from the said line, a signaling device associated with the line and arranged to be operated by the said switch, a suitable connecting circuit for the line, and means for rendering the said signaling device inert when connection is made with the line.

18. In a telephone system, the combination of a metallic telephone line extending from a subscriber's station to a central station where each limb of the line terminates in a number of connection terminals in multiple, a branch from the said metallic line, an electro-thermal switch and a source of electricity in the said branch, a signaling device associated with the line and arranged to be operated by the said switch, a suitable plug-cord circuit for connecting the lines of the system, and means for rendering the said signaling device inert when connection is made with the line.

19. In a telephone system, a metallic line extending from a sub-station to a central station, an electro-thermal switch and a source of electricity bridged across the line, a signaling device arranged to be operated by the said switch, suitable connecting means for the line, and means for rendering the said signaling device inert when connection is made with the line.

20. In a telephone system, a metallic line extending from a substation to a central station, an electro-thermal switch and a source of electricity bridged across the line, a line

signaling device arranged to be operated by the said switch, a plug-cord connecting circuit for the line, a supervisory signaling device associated with the plug-cord circuit, and circuit connections whereby one said signaling device shunts the other out when connection is made with the line and the line is in use.

21. A telephone line, an electro-thermal switch associated therewith, a line lamp associated with the line and connected in circuit with a source of electricity and normally open contacts of the switch, connecting means for the line, a supervisory lamp associated with the connecting means, the said switch being adapted and arranged to close the circuit of the said source through the line lamp when the line circuit is closed, and circuit connections whereby the supervisory lamp shunts the line lamp out and the line lamp shunts the supervisory lamp to keep it from displaying a signal, when connection is made with the line and the line is in use.

22. In a telephone system, a line extending from a subscriber's station to suitable spring jacks at a central station, an electro-thermal switch and a source of electricity bridged across the said line at the central station, a manually-operable switch at the subscriber's station, a line signaling device in circuit with a source of electricity and normally open contacts of the electro-thermal switch, a plug-cord connecting circuit for the line, a supervisory signaling device associated with the plug-cord circuit, the closing of the switch at the subscriber's station causing the electro-thermal switch to close the said normally open contacts and thereby cause the line signaling device to display a signal, and suitable circuit connections whereby the supervisory signaling device shunts the line signaling device and renders same inactive, and whereby the line signaling device shunts the supervisory signaling device and renders same inactive, substantially as described.

23. In a telephone system, a metallic line extending from a subscriber's station to suitable spring jacks at a central station, a transmitter, receiver, bell, and normally open switch at the subscriber's station, an electro-thermal switch and a source of electricity bridged across the limbs of the line at the central station, a line lamp in circuit with the said source of electricity and normally open contacts of the electro-thermal switch, a metallic plug-cord circuit for the line, terminating in suitable connecting plugs adapted to operate with the spring jacks, a test ring for each jack and all connected together and through a suitable resistance to the source of electricity, a third strand for each connecting cord, terminating in a third contact of its connecting plug and adapted to be connected with the test ring of a spring jack when connection is made with the line, a supervisory

lamp in circuit with a said third strand and the source of electricity, and a suitable operator's circuit and busy-test arrangement for the plug-cord circuit, the closing of the normally open switch at the subscriber's station closing the circuit of the said source through the electro-thermal switch and thereby heating same and closing the said normally open contacts therein to light the line lamp, the connecting plug, when connected with a spring jack of the line, placing the line lamp and supervisory lamp in multiple whereby the supervisory lamp shunts the line lamp out and the line lamp shunts the supervisory lamp out, the opening of the switch at the subscriber's station restoring the electro-thermal switch to its normal condition and opening the circuit of the line lamp shunt about the supervisory lamp to allow the latter to glow.

24. The combination with a telephone line circuit, of an electro-thermally-operable device associated therewith and comprising a sealed chamber, heat-producing means within the said chamber, a gas within the said chamber arranged to be expanded by heat from the heat-producing means, a conducting liquid in the said chamber arranged to be moved by the expansion and contraction of the said gas, suitable circuit terminals within the said chamber arranged to be connected or disconnected by the conducting liquid, and suitable circuit connections to the said terminals; a line signaling device arranged to be operated by the said electro-thermally-operable device when the latter is heated by current over the line, and means for shunting the line signal out when connection is made with the line.

25. In a telephone system, the combination of a metallic line extending from a substation to the central station, a switch at the substation for closing and opening the circuit of the metallic line, an electro-thermally-operable device associated with the line at the central station and comprising a sealed chamber, heat-producing coils in circuit with the respective limbs of the metallic line and within the sealed chamber, a gas within the said chamber suitably disposed to be expanded by heat from the heat-producing coils, a conducting liquid in the said chamber suitably disposed to be shifted by the expansion and contraction of the said gas, suitable circuit terminals within the said chamber arranged to be connected or disconnected by the conducting liquid, and suitable circuit connections to the said terminals; impedance coils in circuit with the respective heat-producing coils, a source of electricity in circuit with the said impedance coils, the heat-producing coils, and the limbs of the metallic line, suitable connection terminals connected in multiple to the limbs of the line, a test ring for each connection terminal all connect-

ed together and through a resistance to the said source, a line signal lamp connected in circuit with normally disconnected terminals of the electro-thermally-operable device, the said source, and the said resistance; closing the switch at the substation causing the said device to close the last mentioned disconnected terminals and light the line lamp, a second resistance normally connected in multiple with the other said resistance and cut out of circuit with the said test rings by the said device when the latter is heated, a metallic plug-cord connecting circuit for the line, a third strand of a cord and plug, containing a supervisory signal lamp connected in circuit with the said source and arranged to be connected with the said test rings when connection is made with the line, the super-

visory lamp now being connected in multiple with the line lamp and shunting the latter out, the line lamp also shunting the supervisory lamp to render it inert, and the electro-thermally-operable device opening the circuit of the line lamp and again placing the two said resistances in multiple in the supervisory lamp circuit to light the supervisory lamp, when the switch at the substation is again opened.

Signed by us at Chicago, Cook county Illinois, this 17th day of January, 1903.

FRANK B. COOK.
JAMES G. NOLEN.
